UNITED STATES PATENT OFFICE

CARL F. HAAS, OF SOUTH BEND, INDIANA, ASSIGNOR TO WESTINGHOUSE ELECTRIC
AND MANUFACTURING COMPANY, A CORPORATION OF PENNSYLVANIA

DESIGN FOR A GLOBE FOR A LIGHTING FIXTURE

Application filed June 16, 1930. Serial No. 36,057. Term of patent 14 years.

To all whom it may concern:

Be it known that I, CARL F. HAAS, a citizen of the United States, residing at South Bend, in the county of St. Joseph and State of Indiana, have invented a new, original, and ornamental Design for a Globe for Lighting Fixtures, of which the following is a specification, reference being had to the accompanying drawing, constituting a part hereof.

The figure is an elevational view of a globe for a lighting fixture showing my new design.

I claim:

The ornamental design for a globe for a lighting fixture substantially as shown.

In testimony whereof, I have hereunto subscribed my name this 28th day of May, 1930.

CARL F. HAAS.
